UNITED STATES PATENT OFFICE.

THOMAS COFFELDER, OF DETROIT, MICHIGAN.

RADIATOR.

1,092,242.

Specification of Letters Patent.

Patented Apr. 7, 1914.

Application filed May 17, 1912. Serial No. 898,016.

To all whom it may concern:

Be it known that I, THOMAS COFFELDER, a citizen of the United States of America, residing at Detroit, in the county of Wayne 5 and State of Michigan, have invented certain new and useful Improvements in Radiators, of which the following is a specification, reference being had therein to the accompanying drawings.

- 10 This invention relates to improvements in radiators particularly adapted for use upon motor vehicles, and its object is to provide a construction in which a high cooling efficiency is secured by deflecting and breaking 15 up the air currents as they pass through the radiator, and which presents the appearance of a bank of tubes of rectangular form in cross section arranged in horizontal and transverse rows.
- 20 A further object is to provide a construction which is cheap to manufacture and has other new and useful features. To these ends the invention consists in the matters hereinafter set forth and more particularly 25 pointed out in the claims reference being had to the accompanying drawing, in which—

Figure 1 is a front elevation of a device embodying the invention with parts broken 30 away to show the construction; Fig. 2 is a detail showing a vertical section through a portion of the device; Fig. 3 is a detail showing the same in horizontal section; Fig. 4 is a detail of a fin ribbon; and Fig. 5 is a 35 perspective detail showing a modified construction.

In the drawing 1 represents a top tank and 2 a bottom tank of a radiator construction adapted for use upon motor vehicles, 40 and these two tanks are connected by a series of vertically extending parallel tubes 3, each formed in any suitable manner, as from a sheet of thin metal folded upon itself with its edges soldered together, and with a 45 narrow space between the side walls, thus forming a broad flat tube of a width equal to the desired width of the radiator having a very thin water space. These tubes are connected at their ends in any desired manner 50 to the tanks and are spaced apart by strips or ribbons 4 of thin sheet metal which ribbons are equal in width to the desired distance between adjacent tubes. These ribbons form radiating members or fins on the tubes 55 to provide an extended radiating surface

therefor and assist in cooling the water as it passes through the tubes from the top tank to the bottom tank. The spacing or radiating fins between two adjacent tubes are formed by a single strip or ribbon 4 which is 60 bent into a zig-zag form, extending back and forth across the tubes from the front to the rear edges thereof and forming air passages between the runs or straight portions which 65 passages open through the front and rear sides of the radiator.

Each ribbon is formed with groups of openings 5, as shown in Fig. 4, the ribbon being bent between each group and folded backward to form the next run of the ribbon 70 which extends across the walls of the tubes and is secured thereto between two adjacent tubes in any suitable manner, as by soldering. The bends 6 are preferably so formed that when the core of the radiator is made 75 up, these bends will correspond in width to the width of the tubes and thus give to the front of the radiator the appearance of being formed of rectangular tubes of uniform size and thickness. The openings 5 permit 80 the air entering the air passages at the forward side of the radiator to pass therethrough, the air currents being deflected and broken up as they pass through these openings 5 from the front to the rear side of the 85 radiator.

In the modified construction shown in Fig. 5, the radiating member is formed by a continuous narrow sheet metal strip or ribbon 7 which is soldered or otherwise secured to the face of one wall of adjacent tubes 3 across said face forming a run 8, thence extended in a horizontal or cross run 9 to the opposed face of the other tube and across the face thereof in a downwardly inclined run 95 10 to connect in a like cross run 9 with another run 8 of the ribbon which is secured in a like manner below the first. The ribbon thus extends in a zig-zag form back and forth from front to rear of the radiator and is soldered alternately to one and then the other of the adjacent tube walls with its edge against the wall and projecting laterally therefrom to provide an extended radiating surface. The portions of the ribbon forming the cross runs 9 are preferably 100 turned to present the side of the ribbon to the front of the radiator and the ribbon is preferably of such a width that these portions 9 extending across between the tubes, 110

will correspond in width to the width of the forward edges of the tubes and thus give the desired appearance to the front of the radiator.

5 A very cheap and simple construction is secured by forming the radiating members of continuous strips or ribbons which are easily bent into the desired form and soldered in place between the tubes. In manufacturing the radiator, the strips 4 are first punched in the flat, then folded into the desired zig-zag form by means of a suitable former. The tubes and strips, are then assembled in a suitable holding form to properly space the tubes and hold the ribbons in proper position between them and the ribbons are then soldered to the walls of the tubes in any suitable manner, as by dipping. The several runs of the ribbon extending 10 diagonally across the tubes, deflect the air currents and give an increased cooling effect, the runs forming baffles to arrest the passage of air through the radiator.

Obviously, changes may be made in the 25 construction and arrangement of parts without departing from the spirit of my invention and I do not wish to limit myself to the particular form or construction shown.

Having thus fully described my invention 30 what I claim is:—

1. In a radiator, the combination with spaced walls forming water passages and air spaces between the water passages open at each side for the passage of air therethrough, of a tortuous strip in each air space upon said walls extending across the same from one open side to the other of said space and positioned therein with its bends curved in the direction of the passage of air 35 through said air space to form a baffle therein.

2. In a radiator, the combination with spaced walls forming water passages and air spaces between said water passages opening 45 through the faces of said radiator for the passage of air therethrough, of a continuous metal ribbon in each air space upon the walls thereof extending across the same from face to face of the radiator throughout the length 50 of said walls and formed with a plurality of bends and portions between the bends extending in the direction of the passage of air through said air space.

3. In a radiator, the combination with 55 spaced vertical walls forming water passages, of radiating means on said walls comprising metal strips each formed with a plurality of diagonal portions extending across said walls in the direction of the passage of air through said radiator from front

to rear thereof, and each strip extending from top to bottom of said walls.

4. In a radiator, a core formed with water passages and air spaces between the water passages extending through the core for the 65 passage of air therethrough, and a single continuous metal strip in each air space secured at its edge to a wall thereof and bent into zig-zag form with its inclined portions inclined to the direction of the passage of 70 air through said air spaces and forming baffling means for the air.

5. In a radiator, a core comprising walls forming water passages extending from top to bottom of the core and air spaces between 75 the water passages opening through the front and rear of said core for the passage of air therethrough, and radiating means within the air spaces comprising a continuous metal strip in each air space secured to 80 said walls at its edges and formed of oppositely inclined portions connected by bends and extending across the walls from front to rear of said core and inclined to the direction of the passage of air through the air 85 spaces.

6. In a radiator, a core formed with water passages and air spaces between the passages extending through the core and from top to bottom thereof for the passage of air 90 therethrough, a metal strip within each air space extending from top to bottom thereof and across said space with its edges engaging the walls of the adjacent water passages and provided with openings for the passage 95 of air, said strips each having a plurality of bends curved in the direction of the passage of air through the air spaces.

7. In a radiator, the combination with spaced vertical walls forming water passages and spaces between said water passages for the passage of air through the structure from front to rear thereof, of a continuous metal ribbon in each air space extending from the top to bottom thereof 100 and spanning said space and secured at its edges to the walls, said strip being formed with a plurality of bends and inclined portions extending across the walls from front to rear thereof in the direction of the passage of air through said air space, said strip being also formed with openings in its inclined portions to permit the air to pass through the air space.

In testimony whereof I affix my signature 115 in presence of two witnesses.

THOMAS COFFELDER.
